UNITED STATES PATENT OFFICE

SAMUEL L. BUCHANAN, OF VALPARAISO, INDIANA.

FLYING-MACHINE.

1,080,195.

Specification of Letters Patent.

Patented Dec. 2, 1913.

Application filed April 10, 1911. Serial No. 619,984.

To all whom it may concern:

Be it known that I, SAMUEL L. BUCHANAN, a citizen of the United States of America, residing at Valparaiso, in the county of Porter and State of Indiana, have invented certain new and useful Improvements in Flying-Machines; and I do hereby declare the following to be a full, clear, and exact description of the invention, such as will enable others skilled in the art to which it appertains to make and use the same.

My invention relates to improvements in flying machines and more particularly to the guiding mechanism of the same and its object is to provide the device with improved means for maintaining the aeroplanes horizontal, improved means for operating the rudders of the machine, and to provide the same with various new and useful features as hereinafter described and clearly pointed out in the claim, as will more fully appear by reference to the accompanying drawings in which:—

Figure 1 is a side elevation of a machine embodying my invention; Fig. 2 a front elevation of the same; Fig. 3 a detail of the balancing mechanism for maintaining the planes horizontal; Fig. 4 a detail of the operating mechanism for the horizontal rudder; Fig. 5 the same for the vertical rudder; Fig. 6 a detail in elevation of a portion of the rudder operating mechanism; and Fig. 7 a plan view of the same with portions broken away to show the construction.

Like numbers refer to like parts in all of the figures.

1 represents the aeroplanes of a flying machine, the style shown being a biplane. Obviously a monoplane would not change the essential character of the invention.

2 are ailerons for maintaining the aeroplanes horizontal. Of these there are preferably two at each outer end of each aeroplane, one mounted in front of the other, and each on the outer end of a rock shaft extending inward toward the middle of the machine and thence bent at right angles to form levers as at 4. Pivotated to each lever at its upper end is a connecting rod 5 extending downward and pivoted at the lower end to the outer end of an arm 6 extending from a shaft 7 provided with a lever 8 to oscillate the same, the ailerons at the respective sides of the machine being connected to arms projecting toward the same from the shaft 7 whereby as the shaft is oscillated by

the lever 8 the ailerons at the respective ends of the planes are inclined oppositely from the horizontal whereby as the aeroplane rises at one end and descends at the other, 60 by maintaining the substantially vertical position of the lever 8 the shaft 7 will be so oscillated as to incline the ailerons 2 downward at the lower end of the aeroplanes and upward at the higher end of the same. This 65 obviously tends to restore the aeroplanes to a horizontal position. Thus it is only necessary for the operator to automatically maintain the lever 8 substantially vertical to automatically maintain the aeroplanes horizontal. 70

9 represents horizontal rudders attached to a horizontal shaft at their front, and 10 a vertical rudder pivoted on a vertical axis at its front. A forwardly projecting arm 11 75 is fixed on this shaft to which arm is attached a vertically extended rod 12 adapted to raise and lower the forward end of the arm 11 and thus oscillate the rudders 9. To the upper end of the rod 12 are attached two 80 cords or cables 13 and 14, one of which extends upward over a pulley 15 and the other downward over a pulley 16. These cables thence extend forward to a convenient location where they are attached to a pendulum 85 shaft 17 at opposite sides of its axis and at equal distances therefrom, whereby as the shaft is oscillated as a pendulum the rudders 9 will be oscillated vertically. The pendulum shaft 17 is journaled in a horizontally disposed rocker 18 having a longitudinal slot therein in which are oppositely projecting arms 20 mounted in the shaft 17. To these arms are attached cords 21 which extend back to the rudder 10 and are attached thereto at their rear ends and extended oppositely from the rudder 10 over pulleys 22. Thus when the shaft 17 is rotated by the hand wheel 19 these arms will move the cords oppositely and thus turn the 100 rudder 10 to the right or left about its axis. The operation thus being, that when the shaft 17 is swung as a pendulum the horizontal rudders are turned up and down so that swinging the shaft 17 forward guides 105 the machine upward and swinging it rearward guides the machine downward. At the same time by turning the hand wheel 10 to the right or left the vertical rudder is turned to guide the machine to the right 110 or left as the case may be. The balancing and guiding of the machine is thus by this

mechanism made very simple and obvious, as will readily be understood.

What I claim is:—

A flying machine, comprising a vertical rudder extending forward of its axis, a horizontal rudder at each side of the vertical rudder, a shaft on which the horizontal rudders are mounted, an arm on the shaft and projecting forward therefrom, a rod projecting upward from the forward end of the arm, pulleys respectively above and below the upper end of the rod, cords attached to the rod and extending over the pulleys and thence forward, a pendulum shaft immediately pivoted to turn on a horizontal

axis to which the cords are attached respectively above and below the said axis, oppositely projecting arms on the pendulum shaft, pulleys at opposite sides of the front end of the vertical rudder and cords attached to the arms and extending over said pulleys and thence attached to the front end of the vertical rudder. 20

In testimony whereof I affix my signature in presence of two witnesses.

SAMUEL L. BUCHANAN.
